UNITED STATES PATENT OFFICE.

WILLIAM D. HAILES, OF ROCHESTER, NEW YORK, ASSIGNOR TO GENERAL RAILWAY SIGNAL COMPANY, OF ROCHESTER, NEW YORK.

TRAIN CONTROL.

Application filed November 26, 1924. Serial No. 752,337.

This invention relates to a reversing switch for automatic train control systems.

In train control practice, the progress of the train is usually governed in accordance with control influences communicated from the trackway to suitable receiving devices located on the vehicle. In order that the vehicle may proceed with either end leading, it becomes necessary to change or reverse the connections between these receiving means and the car-carried control means.

It is essential that the switch device employed for making this change of connections be of rugged mechanical construction, that its contacts be heavily insulated, and that the switching mechanism as a whole be protected from moisture, dust, cinders and other foreign matter. In order to provide a switch of this character, it is desirable to use a manually operable switch which can be of a suitably heavy mechanical construction, and can be located in the cab of the vehicle in a position to be adequately protected from moisture or other foreign matter.

It is an object of this invention to provide a reversing switch for automatic train control systems which will be manually operable, at least as to the majority of its contacts, and which may be located at a protected point on the vehicle.

In applying train control systems to existent railway systems, it is found that certain sections of trackway are equipped for automatic train control, while certain other sections are not so equipped. For this reason, means are provided by which, under given control conditions, the car-carried control apparatus may be set to an inactive condition and so maintained until an influence is again received from the trackway. As one set of receiving means only can receive energy when the vehicle is proceeding in a given direction, it is apparent that if a manually operable reversing switch alone were employed, the engineer or train operator could, by manipulation of such switch, prevent the car-carried control apparatus from responding upon the return into territory equipped for automatic train control.

It is another object of this invention to provide means to prevent the operation of a train equipped with a manual reversing

switch from proceeding under certain conditions, at an unrestricted speed unless the reversing switch is properly set.

In the operation of trains it sometimes becomes necessary to make a move against the normal direction of traffic, as for instance in backing into a siding, in taking the slack out of a train or for any other reason. As a manual switch operation for such moves would cause inconvenience and delay, and as these "back-up" moves are usually made at low speeds, it is desirable to allow such movement to be made without a manual switch operation provided they are made at a low speed.

It is a further object of this invention to provide means for permitting a train to proceed against the normal direction of traffic without a manual switch operation, provided such a move is made below a minimum speed limit.

Other objects and advantages of this invention will be pointed out or will become apparent as the description progresses.

In the drawings, a section of trackway equipped for automatic train control, together with the car-carried apparatus embodying the present invention, have been shown in a simplified and diagrammatic manner.

Referring particularly to the trackway, the rails 1 are divided into blocks by the insulating joints 2, the block I and the adjacent ends of two other blocks H and J having been shown. The normal direction of train travel along the trackway is indicated by the arrow.

As the circuits and apparatus used in the several blocks are substantially identical, a description of these circuits and devices in one block only will be given, corresponding elements in the adjacent blocks being identified by like reference characters having distinctive exponents.

Any suitable type of trackway circuits may be used with this invention, and the simplified embodiment shown is a so called two-position single phase system. Referring to the trackway circuits, track signal and train control currents are imposed across the rails at the exit end of each block by means of the track battery 3 and the second-

ary winding of the transformer 4 as shown. The primary winding of the transformer 4 is energized through the contact fingers 5¹ and 6¹ of the track relay 7¹ and the transformer 8¹ which is connected across the transmission line 9 as clearly shown in the drawings.

Wayside signals of the semaphore, light signal or any other suitable type are preferably used in connection with the track circuits. For the purpose of illustration, semaphore signals Z of the type common in railway signaling practice, have been conventionally shown at the entrance end of each block. The means for operating these semaphore signals from the track relays 7 have not been shown, as these means are understood by those skilled in the art, and as these means form no part of the present invention.

A railway vehicle has been conventionally represented in the block I by the wheels and axles 10 and 11. In front of the leading axles 10 and behind the trailing axles 11, over and in inductive relation to the track rails, are mounted two pairs of receiving coils 12 and 13 as shown. The windings of each pair of receiving coils are so connected that currents induced in the coils of each pair by currents flowing in opposite directions in the two track rails will be additive. These receiving coils may or may not be mounted on laminated iron cores. The coils 12 are active, to secure proper control, when movement is in the normal direction of travel, with the pilot first, and coils 13 are so active when movement is in the normal direction of travel (that of the arrow) with the tender first.

The connections between the receiving coils and the other car-carried control apparatus are made through a manually operable reversing switch RS. This switch may be of any suitable construction, but is preferably well insulated and provided with large contacts, and is so mounted as to be protected from moisture, dust, cinders, or other foreign matter. In the simplified form shown, the reversing switch consists of a bar 14 on which are pivotally mounted three movable contact fingers 15, 16 and 17, insulated from the bar 14, and an operating handle 18. The stationary contacts 19, 20, 21, 22, 23 and 24 are provided, and are arranged in such positions as to be engaged by the movable fingers 15, 16 and 17 when these fingers are in their extreme positions as shown. The movable fingers 15, 16 and 17 and the operating handle 18 are pivoted at one end so that the fingers may be swung from one position to the other by means of the operating handle.

An amplifier is provided, and is conventionally represented in the drawings at A. This amplifier is preferably of the type

which acts to respond to weak current impulses in its input circuit and to produce more powerful currents in its output circuit, and may be of the vacuum tube type.

A shaft 25 is geared or otherwise suitably driven from an axle of the vehicle, the connection between the shaft 25 and the axle being represented by a dot and dash line. This shaft 25 carries a gear wheel 26 which operates an automatic reversing switch or check switch. This check switch consists of a toothed sector 27, divided by the insulating section 28 pivoted at the point 29 and carrying a resilient contact arm 30. Two stationary contacts 31 and 32 are provided to cooperate with the contact arm 30 in its two extreme positions. It is obvious that when the shaft 25 is rotated in one direction, corresponding to a given direction of vehicle travel, the sector 27 is thrown to one of its extreme positions and the contact arm 30 is brought into firm contact with one of the stationary contacts, say 31, and is held in that position until the vehicle reverses its direction of travel, when the sector 27 will immediately be thrown to its other extreme position, causing the contact arm 30 to engage the stationary contact 32.

A centrifugal speed responsive device or centrifuge G is also mounted on the shaft 25. This centrifuge has been represented in a simplified form for the sake of clarity, it being understood that any form of centrifuge adapted to this type of system might be employed. The centrifuge illustrated consists of a collar 33 rigidly fastened to the shaft 25, and a collar 34 which is movable on this shaft, these collars being connected by the links 35-36 carrying the weights 37, and being urged apart by the spring 38. The movable collar 34 engages a lever 39 which is pivoted at the point 40 and the free end of which forms a contact arm 42. It is apparent that as the speed of the vehicle increases, the weights 37 will be thrown outwardly, drawing the collar 34 downward against the resistance of the spring 38, and thus causing the contact arm 42 to move over its associated speed contact segments 43 and 44.

A main car relay MR and a non-control relay NC are provided, and operate to make and break circuits for the car-carried apparatus as hereinafter described. These relays may be of any suitable type and are preferably provided with movable contact fingers which are biased by springs, counterweights or other means so that the fingers move to a predetermined position when the relays are de-energized. The contact fingers of these relays are preferably carried on vertically arranged axes, so that their motion will be unaffected by the vibration or swaying of the train. The non-control relay NC is preferably of the slow acting

type, that is, its parts are so constructed and arranged that it will not open its contacts immediately on the de-energization of its windings. This may be accomplished by 5 providing a copper sleeve around the core to sustain the flux therein, or other means may be employed. The purpose of the slow acting feature will be hereinafter disclosed.

An electro-pneumatic valve EPV is provided, and may be of any suitable type 10 adapted for train control practice. It is preferably of a type which acts when de-energized, to effect a breaking action on the train by directly venting the brake pipe, by 15 operating the usual engineer's brake valve, or in any other suitable manner, but it is of such construction that its operation cannot be effected by manual actuation. As the specific type of the electro-pneumatic valve is 20 used is immaterial, a conventional form of valve has been shown, it being understood that any other suitable type of electro-pneumatic valve or brake control apparatus might be used without departing from the 25 spirit of the invention.

A push button PB is provided for picking up the non-control relay NC. This push button is located at some convenient point in the cab of the vehicle within reach of the 30 engineer. This push button PB is enclosed in a box or housing, which is preferably sealed or locked, the key being in the possession of a tower man or other official located at a point where the train passes from 35 trackway territory which is equipped for automatic train control to trackway territory not so equipped.

Operation.—In the drawings, all of the 40 contacts and devices have been shown in their normal operating positions, that is, the positions which would be assumed with the train running at speed and in the normal direction of traffic, over a section of trackway equipped for automatic train control in 45 which clear traffic conditions exist and with the reversing switch set in its proper position.

Assuming that a train is proceeding along 50 the trackway under clear traffic conditions, that is, with no train in the block in which the train is located or in the next block in advance, the leading receiving coils 12 will have currents indicated therein by the train 55 control current flowing in opposite directions in the track rails. These currents will be impressed on the input circuit of the amplifier A through a circuit which may be traced as follows:—from the receiving coils 12, wire 45, stationary contact 22 and movable finger 16 of the reversing switch, wire 46, the input circuit of amplifier A, wire 47, movable finger 15 and stationary contact 20 of the reversing switch, wire 48 to the receiving coils 12. This receiving circuit is 60 resonated to the frequency of the train con-

trol current by means of the condenser M connected across the input circuit of the amplifier A, as shown. The main car relay MR is energized from the output circuit of the amplifier A through wires 49 and 50. The 70 energization of the main car relay MR causes its contact finger 51 to be attracted, closing its front contact and so maintaining an energizing circuit for the electro-pneumatic valve EPV which may be traced 75 as follows:—beginning at the battery terminal B, through contact arm 42 of the speed arm 39, contact segment 44, wire 52, contact finger 51 and front contact of the main relay MR, wires 53 and 54, contact arm 30 80 and stationary contact 31 of the check switch, wire 55, stationary contact 24 and movable finger 17 of the reversing switch, wires 56 and 57 and the winding of the electro-pneumatic valve EPV to the battery 85 terminal C. For the sake of simplifying the drawings, the letters B and C have been used to represent the opposite poles of a source of electrical energy which may be the 90 opposite terminals of a battery.

With the electro-pneumatic valve EPV energized, the train may proceed at speed in the clear block. If the train speed exceeds a maximum limit of, say 60 miles per hour, the contact arm 42 will be moved by 95 the centrifuge G until it no longer makes contact with the segment 44, thus breaking the circuit to the electro-pneumatic valve EPV, traced above, and causing an automatic brake application. This brake application continues until the train speed has 100 been brought below the maximum limit, assumed to be 60 miles per hour, when the contact arm 42 again engages the segment 44 and the electro-pneumatic valve EPV 105 is again energized, to permit releasing the train from the automatic brake application.

Now assume that a train equipped for 110 automatic train control of the type embodying this invention, while running at speed under clear traffic conditions, enters a block in which caution traffic conditions exist, that is, a block in which the train control current is not flowing in the rails because 115 of a train, a broken rail, or other dangerous condition, in the next block in advance. Hence, the receiving coils 12 fail to pick up current and the main relay MR is therefore de-energized, breaking the circuit to the 120 electro-pneumatic valve EPV traced above and causing an automatic brake application. This brake application continues until the train speed has been reduced to a certain minimum value assumed to be 15 miles per hour, when the contact arm 42 engages the 125 segment 43, closing an energizing circuit to the electro-pneumatic valve which may be traced as follows:—from the battery terminal B, through contact arm 42 and segment 43, wires 58 and 57 and the winding 130

of the electro-pneumatic valve EPV to the battery terminal C. The brakes may now be released and the train proceed below the minimum speed limit, until traffic conditions ahead become more favorable.

When a train enters a danger block, that is, a block in which another train is located, or in which other dangerous conditions of trackway exist, the train control current 10 mains cut off from the track rails, and the train may proceed only at a speed below the minimum speed limit in a manner described in connection with a train in a caution block.

Now assume that the train comes to a 15 point on the trackway at which a change from train control territory to territory not equipped for train control is to be made. With the particular simplified type of non-control apparatus shown in this embodiment 20 of the present invention, the engineer will bring the train to a stop at the beginning of the unequipped territory and the tower man or other official at this point will unlock the 25 push button housing and depress the push button PB. Since the train is now in unequipped territory and no train control current is flowing in the track rails, the main relay MR is de-energized, and its back contact 59 is closed. The depression of the push 30 button PB therefore energizes the non-control relay NC through a circuit which is obvious from the drawings, this relay being immediately stuck up through a circuit which may be traced as follows:—beginning 35 at the battery terminal B, through contact finger 59 and back contact of the main relay MR, wires 60 and 61, contact finger 62 and front contact of the non-control relay NC, wire 63 and the winding of the non-control 40 relay NC to the battery terminal C. The non-control relay NC being energized, attracts its contact finger 64, closing the front contact of this finger and completing an 45 energizing circuit for the electro-pneumatic valve EPV, which circuit may be traced as follows:—from the battery terminal B, through contact finger 64 and front contact of the non-control relay NC, wires 65 and 54, contact arm 30 and stationary contact 31 of the check switch, wire 55, stationary contact 50 24 and contact finger 17 of the manual reversing switch, wires 56 and 57 and the winding of the electro-pneumatic valve EPV to the battery terminal C.

The electro-pneumatic valve EPV is now 55 energized and the train may proceed without further restriction in the unequipped territory. When the train again reaches a section of trackway which is equipped for automatic train control, the receiving coils 12 again have currents induced therein by the current flowing in the track rails and the main relay MR is again energized, attracting its contact fingers 51 and 59. The attracting 60 of contact finger 59 breaks its back 65

contact and so opens the stick circuit to the non-control relay NC, causing this relay to retract its contact fingers 62 and 64. As the front contact of finger 51 of the main relay MR is closed, the electro-pneumatic valve 70 EPV is maintained energized through a circuit which has been traced above, and the train may now proceed under the protection of the automatic train control apparatus as 75 described above.

In order that the car-carried apparatus 80 may be returned to its active condition when the train returns to an equipped section of trackway regardless of whether the first block encountered is in the clear or the caution condition, a short permanently energized section of trackway may be provided at the point where the return to train control territory is made. This energized section will always act to energize the main relay MR and so to drop the non-control relay NC, thus placing the car-carried control apparatus in its active condition.

In the practical application of automatic 90 train control systems, it is found that in trackway territory unequipped for automatic train control, stray currents or transients, as they are called, flow in the track rails for short distances. These currents may be caused by the leakage of track circuit 95 signal currents from adjacent track rails, or they may arise from any other source. It is obvious that if a train equipped with the system embodying the present invention encounters these stray currents while 100 operating in unequipped territory, the main car relay MR would be re-energized, causing the non-control relay NC to retract its contact fingers, so placing the train under the control of the automatic apparatus, and causing an automatic brake application 105 bringing the train to a stop after said stray currents ceased to be effective. In order to avoid the delay and inconvenience imposed by such action of stray currents or transients, the non-control relay NC is made slow acting, as hereinbefore pointed out. This slow acting feature enables the non-control relay NC to maintain its contact fingers 62 and 64 attracted for a period of time 110 arranged to correspond to the time required for train travel over the longest stray current section ordinarily encountered in practice.

Now assume that a train is proceeding in 115 unequipped territory with its car-carried control apparatus in the inactive condition, that is, with the non-control relay NC stuck up and the electro-pneumatic valve EPV energized, and also assume that the engineer 120 or train operator endeavors to avoid the resetting of the control apparatus to its active condition upon the return of the train to equipped territory by merely reversing the 125 connections to the receiving coils (without 130

at the same time reversing the direction of travel of the engine) and so connecting the input circuit of the main car relay MR to the trailing receiving coils 13, which cannot receive train control current in any substantial or operative quantity during travel in the direction of the arrow. This change of the manual reversing switch places the movable finger 17 in engagement with the stationary contact 23 and thus breaks the circuit from the non-control relay NC to the electro-pneumatic valve EPV, causing an immediate automatic brake application. This brake application continues until the train speed has been brought down to the minimum speed limit, assumed to be 15 miles per hour, at which speed the contact arm 42 engages the 15 mile per hour segment 43, and the electro-pneumatic valve is re-energized through a circuit which has been traced above. The train may now proceed, but only at the restricted speed of 15 miles per hour, until the manually operable reversing switch is properly set, when the main car relay MR will again be connected up to the active receiving coils and again be energized if coils 12 are receiving current. The reenergization of the main relay MR causes it to attract its contact finger 59, thereby opening the stick circuit to the non-control relay NC and placing the vehicle under the control of the main relay MR.

Now assume that a vehicle equipped for automatic train control of the type embodying this invention leaves the roundhouse, siding or other non-control point and enters an equipped section of trackway. If the manually operable reversing switch is properly set to correspond with the direction of travel of the vehicle, the receiving coils immediately receive energy from the trackway, and the vehicle may proceed at speed until a block in which caution traffic conditions exist is encountered. If, however, the manually operable reversing switch is not properly set, that is, is set in the position corresponding to train travel in the reverse direction from that in which the vehicle is proceeding, the circuit through the main relay MR to the electro-pneumatic valve EPV is broken at the contact finger 17 of the reversing switch, and the brakes are applied until the train speed has been reduced below the minimum speed limit assumed to be 15 miles per hour, at which speed the contact arm 42 engages the speed segment 43, energizing the electro-pneumatic valve EPV through a circuit which has been traced above. The vehicle may now proceed at the minimum speed until the manually operable reversing switch is properly set.

In railway practice it is sometimes necessary to make short moves, usually at a low speed and for varying distances, against the normal direction of traffic, as in taking the

slack out of a train, in backing into a siding or for any other reason. It is desirable that such back-up moves should be permitted without the delay or inconvenience imposed by a manual actuation of the reversing switch. Since the length of such back up move is indeterminate, it is not thought desirable to limit the train operator or engineer as to the distance of travel of such moves, but as a train running in a direction against the normal direction of traffic is a hazard to following trains, it is thought desirable to limit the speed at which such back-up move may be made. This invention provides that such back-up movement, in equipped territory only, can be made without necessity for operation of the reversing switch RS provided the speed be kept within a low speed limit.

Assume now that a train, stopped in territory equipped for automatic train control, makes a short back-up move, the manually operable reversing switch remaining in its forward running position. The sector 27 is thrown into its reversed running position by the gear wheel 26 causing the contact member 30 to disengage the stationary contact 31 and to engage the stationary contact 32. This breaks the circuit to the electro-pneumatic valve EPV through the main car relay MR, but the electro-pneumatic valve EPV remains energized through a circuit including the 15 mile per hour speed segment 43, so long as the train speed does not exceed the assumed minimum limit of 15 miles per hour. Thus back-up moves in equipped territory may be made without the operation of the manually operable reversing switch, provided the minimum speed limit is not exceeded. Also, if such back up movement in equipped territory be accompanied by operation of reversing switch RS, the speed is still restricted to the low speed limit, since under these conditions, relay MR is down and EPV can be energized only through low speed contact 43.

If, in equipped territory, the engineer attempt to defeat this system, by simultaneously reversing switch RS and the direction of travel of the train, MR being down due to being deprived of current from the receiving coils 13, the speed of the train is limited by the low speed contact 43.

On the other hand, while not at all probable, should the switch RS be reversed and the direction of train movement also reversed, in unequipped territory, relay NC already being up, EPV would be energized through a circuit including finger 64 and front point of NC and fingers 30 and 17 of the automatic and manually operated switches respectively, so that the train speed would not be restricted to the low speed limit, by low speed contact 43. This

however is not particularly undesirable since in non-train control territory the train is taken out from under control of the brake applying device EPV and is put 5 wholly within control of the engineer so that he is not restricted in his operation of the train and knows that the full responsibility rests on him.

It is to be understood that the specific 10 embodiment of this invention which has been shown and described has been disclosed for the purpose of explaining the nature of the invention rather than for the purpose of limiting its scope. It should 15 be further understood that many additions, modifications and combinations could be made without departing from the spirit of the present invention. For instance, a polyphase car relay might be used, imposing 20 different speed restrictions in caution and danger blocks, the setting up of the non-control relay might be accomplished by means of special trackway apparatus located at the point of the beginning of non-control 25 territory, or many other changes, additions or modifications might be made.

What it is desired to secure by Letters Patent is:—

1. In an automatic train control system, 30 car-carried control apparatus for controlling the brakes of a vehicle, two sets of receiving means for inductively receiving influences from the trackway, a manually operable reversing switch associated with 35 said sets of receiving means, an automatic check switch controlled by the direction of travel of the vehicle and associated with said brake controlling apparatus and said manually operable reversing switch, and 40 means for imposing a restrictive speed limit on the vehicle if said manually operable reversing switch is set for a direction of vehicle travel opposite to that in which the vehicle is proceeding.

2. In an automatic train control system, 45 car-carried apparatus comprising, a brake control device, a main relay, a manually operable reversing switch having two operating positions for controlling a circuit to 50 said main relay, a speed-responsive control device and an automatic check switch acting while the train is traveling in a given direction to control said brake control device by said main relay when said manually operable reversing switch is in one position, and to control said brake control device by 55 said speed responsive control device when said manually operable reversing switch is in the other position.

3. In an automatic train control system 60 of the type in which control influences corresponding to traffic conditions are inductively transmitted from the trackway to a moving vehicle, car-carried apparatus 65 including two sets of receiving means, a

two-position manually operable reversing switch, a brake control device, a speed governed control means associated with said brake control device for imposing a high or a low speed restriction and a check switch operated by the direction of travel of the vehicle and electrically associated with said manually operable reversing switch, said check switch acting while the train is traveling in a given direction to 70 impose said low speed limit if the manually operable reversing switch is in one position and to impose said high speed limit if the manually operable reversing switch is in the other position. 80

4. In an automatic train control system of the type in which control influences corresponding to traffic conditions are inductively received from the trackway, car-carried brake control apparatus comprising two sets of influence receiving devices, one of said sets receiving said influences when the vehicle is proceeding with one end leading and the other of said sets receiving said influences when the vehicle is proceeding 90 with the other end leading, a main relay, a manually operable reversing switch for connecting said main relay alternately to each of said sets of receiving devices, a check switch operated by the direction of travel 95 of the vehicle, and a brake applying device, said main relay controlling said brake applying device through a circuit including a contact of said check switch and a contact of said manually operable reversing switch. 100

5. In an automatic train control system of the type in which control influences correspondent to traffic conditions are inductively transmitted from the trackway to a moving vehicle, car-carried apparatus including two 105 sets of influence receiving devices, a manually operable reversing switch, a brake control device, and a check switch operated by the direction of travel of the vehicle, said check switch being electrically associated 110 with said manually operable reversing switch and cooperating therewith to render said brake control device active if said manually operable circuit controller is not in a position to correspond with the direction of 115 travel of the vehicle.

6. In an automatic train control system, vehicle-carried control apparatus comprising two sets of receiving devices, a main relay, a two-position manually operable reversing switch for alternatively connecting each of said sets of receiving devices with said main relay, a check switch operated by the direction of travel of the vehicle, a brake control device, a speed governed switch having a contact opened at a high speed and a contact opened at a low speed, and a control circuit for said brake controlling means, controlled jointly by said high speed contact of said speed governed switch and a 125 130

contact of said main relay when said manually operable reversing switch is in one position, and by said low speed contact of said speed governed switch when said manually operable reversing switch when said manually operable reversing switch is in its other position for a given direction of vehicle travel.

7. In an automatic train control system of the type in which control influences 10 responding to traffic conditions are inductively transmitted from the trackway to a moving vehicle, car-carried apparatus comprising two sets of receiving devices, means for controlling the brakes of a vehicle, a two-position manually operable reversing switch having an auxiliary contact, controlled by the direction of travel of the vehicle, and means including said manually operable reversing switch for operating said brake control means in accordance with said control influences when said manually operable reversing switch is in one position and for 20 imposing a low speed restriction when said manually operable reversing switch is in its 25 other position for a given direction of vehicle travel.

8. In an automatic train control system, vehicle-carried apparatus comprising, means for inductively receiving control influences 30 from the trackway, means for controlling the brakes of the vehicle in accordance with such influences, and a reversing switch for connecting said receiving means to said brake controlling means including a manually operable contact finger and a contact 35 operated by the direction of travel of the vehicle, said contacts cooperating to close a circuit to said controlling means only when said manually operable contact is in a position 40 corresponding to the direction of travel of the vehicle.

9. In an automatic train control system, two sets of receiving devices for receiving control influences from the trackway, a manually operable reversing switch associated 45 with said receiving devices, an automatic check switch controlled by the direction of travel of the vehicle, and means for imposing a restrictive control upon the vehicle if said manually operable reversing switch and said automatic check switch are not in corresponding positions.

10. In an automatic train control system for railroads, the combination of influence 55 transmitting means partly on the vehicle and partly along the trackway for transmitting control influences from the trackway to the vehicle, speed restricting apparatus governed in accordance with traffic 60 conditions ahead through the medium of said influence transmitting means, said apparatus including a brake setting appliance which applies the brakes of the train if the speed of the train is excessive, and means 65 governed in accordance with the direction

of movement of the vehicle for restricting the speed of the vehicle to below a low limit if the vehicle is moved backwards regardless of the then existing traffic conditions.

11. In an automatic train control system 70 of the continuous inductive type, the combination of influence receiving elements located over the trackway in front of the first axle of the train adapted to have voltages induced therein in response to alternating 75 train control current flowing down one track rail through the axles of the train and back through the other rail, speed control mechanism including a brake setting appliance which permits the train to travel at a high 80 speed without incurring a brake application while the train is moving forward and train control current is flowing in said track rails, and means for causing said speed control mechanism to permit the train to proceed 85 only within a low speed limit effective if the direction of movement of the train is reversed at a point where train control current is flowing in said track rails.

12. An automatic train control system of 90 the continuous inductive type comprising, a normally energized brake setting appliance, means including a speed responsive device for maintaining said brake setting appliance energized in response to the flow of 95 train control current flowing down one track rail through the wheels and axles of the train and back through the other rail and which restricts the train to a low speed 100 limit if the flow of train control current in the track rails is cut off, and means governed in accordance with the direction of movement of the train effective to permit the train to proceed only within a low speed 105 limit if the direction of movement of the train is reversed in territory where train control current is flowing in said track rails.

13. An automatic train control system comprising, a normally energized brake 110 setting appliance, influence communicating means for transmitting control influences from the trackway to the vehicle in accordance with traffic conditions ahead, speed control mechanism setting up a high speed 115 limit under favorable traffic conditions and setting up a low speed limit under unfavorable traffic conditions ahead which effects de-energization of said brake setting appliance and effects a brake application if the speed limit is exceeded, and means governed in accordance with the direction of movement of the train effective to restrict the train to travel within a low speed limit if the direction of movement of the train is 120 reversed regardless of the then existing traffic conditions.

14. In an automatic train control system, two sets of receiving devices for receiving control influences from the trackway, a man- 130

ually operable reversing switch associated with said receiving devices, and automatic switch means governed in accordance with the direction of travel for preventing mis-
use of the said reversing switch.

15. In an automatic train control system, two sets of receiving devices for receiving control influences from the trackway, a man-
ually operable reversing lever associated

with said receiving devices, and an auto-
matically operated switch governed by the
direction of vehicle travel for imposing a
penalty if the reversing switch and the di-
rection of travel of the vehicle are not in
correspondence.
